UNITED STATES PATENT OFFICE.

LEONARD S. TURNER, OF COIN, IOWA, ASSIGNOR OF ONE-HALF TO HENRY GLORE, OF COIN, IOWA.

ROPE-MAKING MACHINE.

No. 800,774.

Specification of Letters Patent.

Patented Oct. 3, 1905.

Application filed April 25, 1905. Serial No. 257,349.

To all whom it may concern:

Be it known that I, LEONARD S. TURNER, a citizen of the United States, residing at Coin, in the county of Page and State of Iowa, have 5 invented a new and useful Rope-Making Machine; and I do hereby declare the following to be a full, clear, and exact description of the invention, such as will enable others skilled in the art to which it appertains to make and 10 use the same.

This invention relates to rope-making machines; and the object of said invention is to provide a device of this character which is simple in construction and inexpensive to 15 manufacture.

More especially the invention provides means consisting of tracks having a ratchet-bar on one side thereof, said tracks being adapted to carry slidably thereon a carriage 20 adapted to hold the middle portion of the strands which compose the rope when made. Said carriage carries a spring-actuated pawl to engage the ratchet upon the tracks, and the other end of said tracks is provided with a 25 revolving head having hooks adapted to twist each respective strand of the rope.

Other and further objects and advantages of the invention will be hereinafter set forth, and the novel features thereof defined by the appended claims.

My invention is illustrated in the accompanying drawings, which, with the figures of reference marked thereon, form a part of this application, and in which drawings—

35 Figure 1 is a side elevation of my improved rope-making machine, illustrating the required number of strands of the rope before twisting. Fig. 2 is a side elevation, partly in section, showing a portion of the rope made 40 complete. Fig. 3 is a section on line 3 3 of Fig. 1 looking in the direction of the arrow. Fig. 4 is a detail perspective view of the guide-piece separating the strands of rope before twisted. Fig. 5 is a sectional view on line 5 5 45 of Fig. 6. Fig. 6 is a detail perspective view of one end of the machine with the guide-piece removed. Fig. 7 is a detail view of the rope, showing the loops formed at the end of each strand which compose the main portion 50 of the rope and also showing the other end of the rope adapted to be inserted through said loops to form a complete loop at the end of the rope, as illustrated in Fig. 8. Fig. 8 is a detail view of the complete loop formed on

the end of the rope, and Fig. 9 is a detail view 55 of two strands of suitable material forming the rope.

Referring to the drawings by figures, 1 designates the guide-tracks of the machine, having a carriage mounted thereon, consisting of 60 a base 2, having vertically-disposed walls 3 at one end of said base adapted to receive the shank portion 4 of the guide-piece 5. Each vertical wall 3 is provided with vertical recesses 6 and 7, the recess 7 being provided 65 with a pivotally-mounted latch 8, adapted to securely hold said guide-piece 5 in correct vertical position to coöperate with the strands of rope. The base of the carriage 2 is provided with a slot 9, and pivotally mounted in 70 said slot is a spring-actuated pawl 10, adapted to be engaged by the hook 11 of the spring-arm 12, formed integral with the coiled spring 13, said spring being secured to the base, as at 14. Said spring-actuated pawl is 75 adapted to engage the rack-bar 15, secured to the side of one of the guide-tracks 1. At the other end of the base 2 a vertically-disposed standard 16 is provided having a horizontal 80 cross-piece 17 secured to the face of the standard 16, and the other end of the horizontal cross-piece 17 is secured to a vertically-disposed portion 18, located between the walls 3. This cross-piece is for the purpose of forming 85 a rigid framework for the carriage.

Mounted at the top of the vertical standard 16 is the body portion of the hook 19, having a rear shank 20, the end of which is screw-threaded, as at 21, and adapted to receive a screw-threaded lock-nut 22, said lock-nut being provided for the purpose of holding the disks 23 in their correct relative positions to coöperate with balls 24, adapted to be inserted between said disks 23, said disks being provided with runways 25 and said runways adapted to contain the balls 24. This construction is for the purpose of providing an easy revolving movement for the body portion of the hook 19. Projecting from the body portion of the hook 19 is a hook 26, 90 which is adapted to receive or hold the required number of strands of rope to be twisted. The guide-piece 5 is provided on its vertical edges with recesses 27, said recesses being inclined toward one another, as shown in Fig. 1, Fig. 2, and Fig. 4. The rear portion of said guide-piece is provided with a recess 28, adapted to receive the hook 26 to 100 105

prevent said hook from turning before the desired twist is obtained upon each strand of the rope.

In the present invention I have illustrated 5 four strands of rope; but I am not desirous of limiting myself to any special number of strands. Said four strands 29, that compose the rope, consist of two pieces 30, laid parallel to one another and bent on line X X, as 10 shown in Fig. 9, which forms two loops 31. Said loops are then placed over the hook 26, as seen in Figs. 1 and 2, after which four strands are hanging therefrom. Then each strand is placed, respectively, in the recesses 15 27. This is for the purpose of holding them separated.

Located at the end 32 of the guide-tracks 1 is a bifurcated standard 33, adapted to hold a pulley 34 between said bifurcated end 35 of 20 the standard 33. Projecting from the rear face of the standard 16 is an eye 36, adapted to be connected by a rope 37, said rope being adapted to engage the pulley 34. Said rope has a weight 38 at the end thereof, said weight 25 being adapted to counterbalance the twisting action upon said strands—that is, when the revolving head is being operated. At the end 39 of the guide-tracks 1 a standard 40 is provided having a rigid disk 41, and located on 30 one side of said disks is a revolving disk 42, having a circumferential flange 43. Said flange 43 is provided on its inner face with gear-teeth 44, adapted to engage a plurality of pinions 45, said pinions being provided 35 with shafts 46, the ends of which are turned to form hooks 47, adapted to be engaged by each strand of the rope, as shown in Figs. 1 and 2 of the drawings. The revolving disk having the flange is mounted upon a shaft 48, which is mounted in the rigid disk 41, 40 said shaft 48 being provided with a nut 50 to securely hold said flanged disk in relative position to coöperate with the four pinions 45. Projecting from one face of said flanged disk is 45 an arm 51, having a crank-handle 52, which is adapted for the purpose of operating the flanged disk for the purpose of revolving each respective pinion 45, which are provided with revolving hooks 47, which are connected to 50 each respective strand of the rope.

The operation is as follows: As before stated, two strands of suitable material for making rope are laid parallel to one another and then folded on line $\pi\pi$, as shown in Fig. 55 9, the folded portions of which form loops, which are placed over the hook 26. Said hook is then inserted in the recess 28 in the guide-piece 5 to prevent the same from turning. After the two strands are folded on line 60 $\pi\pi$ and placed over said hook four strands are left hanging therefrom, each strand being then placed in each respective recess 27, as shown in Fig. 1, after which the end of each strand is hooked over the hooks 47. The 65 flanged disk is then rotated. The flange of said

disk being provided with gear-teeth upon the inner circumference causes the plurality of pinions to rotate, the shafts of said pinions terminating in hooks 47, which are connected to each respective strand, as before stated. 70 The flanged disk is rotated until the desired twisting tension is obtained upon each respective strand. Then the guide-piece is moved toward the revolving flanged disk, after which a complete rope is made, as shown clearly in 75 Fig. 2 of the drawings. The ends of each respective strand, which are hooked over the hooks 47, are brought into registration, as shown in Fig. 7, and then the other end, which is placed over the hook 26, is inserted through the loops, as shown in Fig. 7, ready to be inserted, as shown, to complete a larger loop, as shown in Fig. 8.

Of course it is distinctly understood that various changes may be made in the details 80 of construction and combinations of parts other than those illustrated in the accompanying drawings, if desired, without in any way departing from the spirit and scope of the invention.

Having thus fully described my invention, 85 what I claim as new, and desire to secure by Letters Patent, is—

1. A rope-making machine, having guide-tracks, a carriage mounted thereon, a revolving hook to engage each respective strand, means to hold each strand separated, means upon said first-named means to prevent the revolving hook from turning before the desired twist is obtained upon the said respective strands, means to allow said revolving hook to have a smooth revolving movement, and means to twist each respective strand to the desired tension to cause the said rope to be formed.

2. A rope-making machine, having guide-tracks, a carriage mounted thereon, a rack-bar upon one side of one of the guide-tracks, a spring-actuated pawl to engage said rack-bar, a revolving hook upon said carriage to engage each respective strand, means to hold each strand separated, means upon said first-named means to prevent the revolving hook from turning before the desired twist is obtained upon the said respective strands, means to allow said revolving hook to have a smooth revolving movement, a weight to counterbalance said twisting action, a revolving flanged disk, and means to be engaged by said revolving flanged disk to twist each respective strand to the desired tension to cause said rope to be formed.

3. A rope-making machine, having guide-tracks, a carriage mounted thereon, a revolving hook to engage each respective strand, means to hold each strand separated, means upon said first-named means to prevent the revolving hook from turning before the desired twist is obtained upon the said respective strands, means to allow said revolving

hook to have a smooth revolving movement, and means to twist each respective strand to the desired tension to cause said rope to be formed.

5 4. A rope-making machine, having guide-tracks, a carriage mounted thereon, a rack-bar upon one side of one of the guide-tracks, a spring-actuated pawl to engage said rack-bar, a revolving hook upon said carriage to engage each respective strand, means to hold each strand separated, means upon said first-named means to prevent the revolving hook from turning before the desired twist is obtained upon the said respective strands, means

to allow said revolving hook to have a smooth 15 revolving movement, a weight to counterbalance said twisting action, a revolving flanged disk, and means to be engaged by said revolving flanged disk to twist each respective strand to the desired tension to cause said rope to be 20 formed.

In testimony whereof I have hereto affixed my signature in the presence of two witnesses.

LEONARD S. TURNER.
